UNITED STATES PATENT OFFICE.

HARRY A. DOUGLAS OF BRONSON, MICHIGAN, ASSIGNEE TO DOUGLAS & RUDD MFG. CO.
OF BRONSON, MICHIGAN, A CORPORATION OF MICHIGAN.

METHOD OF FORMING CYLINDRICAL SHELLS AND ASSEMBLING THEM WITH CORES.

1,256,666.

Specification of Letters Patent. Patented Feb. 19, 1918.

Application filed July 7, 1916. Serial No. 107,902.

To all whom it may concern:

Be it known that I, HARRY A. DOUGLAS, citizen of the United States, residing at Bronson, in the county of Branch and State 5 of Michigan, have invented a certain new and useful Improvement in Methods of Forming Cylindrical Shells and Assembling Them with Cores, of which the following is a full, clear, concise, and exact description, 10 reference being had to the accompanying drawings, forming a part of this specification.

My invention relates to structures employing tubular shells and cores surrounded 15 thereby, such for example as are found in circuit couplers or connectors, the invention having for its object the provision of an improved method of forming the shells and combining them with their contained cores.

20 In practising my invention I employ a substantially parallelogrammatic sheet of metal and form in parallel edges thereof complementary parts of interlocking joints, these complementary parts being desirably in 25 the form of dovetail shaped mortises and tenons. A sheet of metal thus modified is rolled or curled into a tube that is desirably cylindrical, the edge portions of the sheets in which the complementary elements of the 30 interlocking joints are formed being brought into butt engagement with the complementary members of the joints interlocking. A core adapted for tight driving fit within the bore of the shell is driven into the shell interior 35 whereby the tenons and mortises are tightly pressed against each other at the abutting dovetailed or interlocking faces thereof. The core, by effecting this tight engaging pressure between the interlocking elements 40 of the joints prevents those elements from being moved out of the contour of the shell thereby to maintain such contour. The core also prevents the shell from being collapsed since neither of the portions marginalizing the 45 abutting meeting edges of the curled sheet can be inwardly pressed at the core.

In accomplishing these results the core itself is tightly held in place to have the desired assembly with the shell.

50 I will explain my invention more fully by reference to the accompanying drawing in which Figure 1 shows a sheet of metal having the formations thereon that enable it to be curled into a tubular shell; Fig. 2 shows 55 the sheet of Fig. 1 curled with one of the

edge portions to be locked superposed upon the other in position to enable these edge portions to be brought into interlocking engagement; Fig. 3 shows the completed tube; Fig. 4 shows the core and shell about to be 60 assembled; Fig. 5 illustrates the core and shell in assembly; and Fig. 6 is a longitudinal sectional view of the product with other parts complementary thereto when such product is in the form of a circuit connector. 65

Like parts are indicated by similar characters of reference throughout the different figures.

The circuit coupler or contact carrier illustrated includes a cylindrical metallic shell 70 or tube 1 in which there is tightly inserted a contact carrying core 2 of insulating material and which carries spring pressed contacts 3 and 4 designed respectively for engagement with contacts 5 and 6 carried respectively by the plug 7 and lamp base 8, the elements 7 and 8 having additional terminals 9 and 10 which are in the form of metallic shells that are electrically connected by the metallic shell 1 when the elements 7 and 8 75 are received in the ends thereof. The contact carriers 7 and 8 are provided with bayonet pins 11 and 12 which are respectively receivable within bayonet slots 13 and 14 formed in the shell 1, this shell being thus 80 adapted mechanically to couple the carriers 7 and 8 to include their contacts 5 and 6 in circuit by way of the electrically connected contacts 3 and 4 and their contacts 9 and 10 in circuit by way of the metallic shell 1 itself. 85

In making this device a stamping is formed, as illustrated in Fig. 1, which is afterward curled to form a cylinder or tube by the steps illustrated in Figs. 2 and 3, the dovetailed tenons 15, 16 being received 90 within correspondingly shaped dovetailed mortises 17 and 18 respectively included in the same zone with said tenons and within the circle or contour of the shell, the formations 15, 16 and 17, 18 constituting interlocking elements at the abutting meeting edges of the seam. The edges of the curled sheet of metal thus meet or abut instead of overlapping whereby no thickened or projecting seam results, the dovetail formations 100 affording abutting edge surfaces that are inclined with respect to the axis of the shell. The core is driven under reasonable pressure into the cylinder 1 to force the inclined surfaces of the tenons tightly into abutting 105 110

engagement with the inclined surfaces of the mortised portions, whereby tendency to destroy the circle or contour of the tube is guarded against. When the circle of the cylinder has been firmly established by the core, any enlargement of the circle is obviously guarded against owing to the dovetailed formation of the mortises and tenons, and the intermeshing edge portions of the rolled sheet are kept within the contour of the cylinder owing to the firm pressure of the dovetail faces of the tenons upon the dovetail faces of the mortises, this pressure being exerted by the plug that is tightly driven or forced into the bore of the shell. The core acts also to guard against the collapsing of the tube 1 since neither of the portions margining the abutting meeting edges of the curled sheet can be inwardly pressed at the core.

Having thus described my invention I claim as new and desire to secure by Letters Patent the following:

1. The process of forming a shell and assembling it with a core therefor which consists in forming interlocking dovetailed joint elements in two parallel edge portions

of a sheet of metal; curling the sheet of metal into a tube and bringing said parallel edge portions into abutting engagement and the dovetailed joint elements into interlocking relation; and forcing the core into the bore of the shell to effect and maintain tight engaging pressure between the inclined edge portions of the dovetailed joint elements. 30 35

2. The process of forming a shell and assembling it with a core therefor which consists in forming interlocking joint elements in two parallel edge portions of a sheet of metal; curling the sheet of metal into a tube and bringing said parallel edge portions into abutting engagement and the joint elements into interlocking relation; and forcing the core into the bore of the shell to effect and maintain tight engaging 40 45 pressure between the interlocking joint elements.

In witness whereof, I hereunto subscribe my name this 24th day of June, A. D., 1916.

HARRY A. DOUGLAS.
